UNITED STATES PATENT OFFICE.

WADE T. BROWN, OF WILLIAMSBURG, VIRGINIA.

SANITARY LID-COVER.

1,133,091.

Specification of Letters Patent. Patented Mar. 23, 1915.

Application filed February 3, 1914. Serial No. 616,234.

To all whom it may concern:

Be it known that I, WADE T. BROWN, a citizen of the United States, residing at Williamsburg, in the county of James City 5 and State of Virginia, have invented certain new and useful Improvements in Sanitary Lid-Covers; and I do hereby declare the following to be a full, clear, and exact description of the invention, such as will enable others skilled in the art to which it 10 pertains to make and use the same.

This invention relates to sanitary lid covers, and one of the principal objects of the invention is to provide a sanitary paper cover for the toilet bowl, which can be readily detached from a roll affixed in a bracket at the side of the wall in the toilet room.

Another object of the invention is to provide a sanitary paper cover for the lid of a 20 toilet bowl, said cover having a depending flap to protect the user against the possibility of contracting diseases, said paper cover being connected to a roll mounted in a bracket and said covers each being readily 25 detachable from the roll as desired.

These and other objects may be attained by means of the construction illustrated in the accompanying drawing, in which,

Figure 1 is a plan view of a sanitary paper lid cover made in accordance with this 30 invention, Fig. 2 is a side elevation of a bracket or holder for a roll of sanitary lid covers, and Fig. 3 is a front elevation of the same.

Referring to the drawing, the numeral 1 35 designates a sanitary paper lid cover, having oppositely curved sides 2 and a central aperture 3 having an inwardly extending

flap 4 adapted to be turned down into the cover of the bowl in front. The covers 1 are 40 connected together along the line 5 by perforations, while the central portions 6 are separated from the next adjacent cover. The covers in the roll are folded on the lines 7, and the roll 8 is supported in a suitable 45 holder or bracket 9 having a base 10 adapted to be secured to a suitable support.

From the foregoing it will be obvious that the sanitary lid covers may be quickly disconnected by drawing one out of the 50 bracket and separating it from the roll on the perforated line 5, after which the cover is unfolded and placed in position for use.

A sanitary cover made in accordance with this invention can be supplied in rolls at 55 low cost and is in the line of sanitary progress, and should meet with the approval of the public in general.

What is claimed is:—

A roll of sanitary lid covers each formed 60 of paper and provided with curved sides, straight ends, a central aperture, said covers being separated one from the other in the series at the central longitudinal portion, and said covers being connected in series, one to the next adjacent cover in the roll by 65 a line of perforations at each side of said central detached portion, and said covers being folded inwardly at the opposite sides to form a comparatively narrow roll. 70

In testimony whereof I affix my signature in presence of two witnesses.

WADE T. BROWN.
